(57) **CLAIM**

I claim the ornamental design for a solar illumination device, as shown and described.

DESCRIPTION

FIG. 1 is an illustration of a top perspective view of the solar illumination device.

FIG. 2 is side elevation illustrating the left side of the solar illumination device.

FIG. 3 is a side elevation illustrating the right side of the solar illumination device.

FIG. 4 is a back elevation view of the solar illumination device.

FIG. 5 is a front elevation view of the solar illumination device.

FIG. 6 is a top view of the solar illumination device.

FIG. 7 is a bottom view of the solar illumination device.

FIG. 8 is a front perspective view of the solar illumination device mounted on a support.

FIG. 9 is a side view illustrating the left side of solar illumination device mounted on a support; and,

FIG. 10 is a side view illustrating the right side of the solar illumination device mounted on a support.

In the drawings, broken lines depict environment or unclaimed subject matter only and form no part of the claimed design.
